[57] CLAIM

The ornamental design for a ceiling fan cover plate, as shown and described.

DESCRIPTION

FIG. 1 is a plan view of a ceiling fan cover plate showing my new design;

FIG. 2 is a side elevational view thereof; and

FIG. 3 is a perspective view thereof.

The broken line representation of a ceiling fan in FIG. 3 is for purposes of illustration only.

FIG. 1

FIG. 2

FIG. 3
